UNITED STATES PATENT OFFICE.

EDGAR J. MARTEL, OF LACONIA, NEW HAMPSHIRE.

AUTOMOBILE SWITCH LOCK.

Original application filed July 1, 1921, Serial No. 481,769. Divided and this application filed November 11, 1922. Serial No. 600,320.

To all whom it may concern:

Be it known that I, EDGAR J. MARTEL, a citizen of the United States, residing at Laconia, in the county of Belknap and State of New Hampshire, have invented new and useful Improvements in Automobile Switch Locks, of which the following is a specification.

This invention relates to automobile locks more especially of that type designed to lock the ignition switch. According to this invention not only is the ignition switch locked in off position, but provision is also made for locking the lighting switch in any position on or off, as may be desired, at the same time. While not limited to such use, this invention has been designed to be used in conjunction with a device for locking the clutch and brake pedals of the machine, the whole combination and the pedal lock per se being described and claimed in my application for patent Serial Number 481,769, filed July 1, 1921, entitled automobile locks, of which the present application is a division.

For a more complete understanding of this invention, reference may be had to the accompanying drawings in which—

Figure 1 is a front elevation partly broken away of the ignition and lighting switches and the lock and the casing for these parts.

Figure 2 is a section on line 2—2 of Figure 1.

Figure 3 is a section on line 3—3 of Figure 1.

Figure 4 is a detail of the locking bolt showing the ignition disk switch in dotted lines.

Figure 5 is a side view of the ignition switch showing the locking bolt in dotted lines.

Figure 6 is a diagram of the ignition and lighting circuits at the dashboard.

Referring to these figures, 30 indicates a casing adapted to be made fast to the dashboard of a vehicle and containing the switch mechanisms controlling the ignition circuit for the engine and the lights for the car, the lighting switch operating handle being indicated at 40 and the ignition switch handle 41. The handle 40 is fixed to a shaft 42 extending within the casing and carries therein a disk 43 of insulating material. As

shown more particularly in Figure 3 this

disk carries a metallic contact 44 which may be brought in turn into bridging contact between pairs of spring terminals such as shown at 45 and 46. The handle 41 is similarly fixed to a shaft 47 carrying within the 60 casing a disk of insulating material 48 lying in the plane of the disk 43 and adjacent thereto and which carries also a similar metallic contact element 49 which may make bridging contact between the terminals 50 65 and 51 of the ignition circuit.

A single pair of terminals only is required for the ignition circuit, but the lighting circuit requires a plurality of such pairs, in the present embodiment three being 70 shown, one pair being indicated at 45 and 46 and similar pairs adjacent thereto being indicated at 53 and 54 and 55 and 56. For example, the terminals 53 and 54 when connected by the metallic bridge 44, may close 75 the circuit for bright lights, while the contacts 45 and 46, when bridged, may close the circuit for dim lights, and the contacts 55 and 56, when bridged, may close the contact for curb light. For holding the switch 80 yieldingly in any of its positions the outer edge of the disk 43 has a series of notches or depressions 57 therein for engagement by a spring finger 58 mounted at one end of a leaf spring 59 fixed at its other end to the 85 wall of the casing. It will be noted that there is one more notch 57 than pairs of contacts for the various lighting circuits, the additional notch serving to hold the disk in position where no contacts are bridged, this 90 being the off position of the switch when no lights are burning. The disk 48 is similarly provided with a pair of notches 60 with which cooperates a spring finger 61 carried at the end of a leaf spring 62 fixed 95 to the casing, these notches determining on and off positions for the ignition. The disk 43 also has a series of rectangular notches 65 corresponding in number and relative position to the notches 57, while the disk 48 has a similar notch at 66, there being one such notch only in this disk. These notches are so positioned that when the ignition circuit is in off position, in which case the contact 49 fails to bridge the contacts 50 and 51, the notch 66 will be substantially opposite to one of the notches 65 of the disk 43, the disks 43 and 48 being positioned in the same plane.

A locking bolt or plunger 70 is mounted 110

in a guideway 71 fixed to the rear face of the casing 30 in position so that its forward end may be projected transversely of the plane of the disks 43 and 48 within the slots 65 and 66 so that when in projected position both disks 43 and 48 are locked against turning movement. This locking bolt is projected by means of a lever 72 pivoted at 73 to a portion of the casing and having a slot at its upper end at 74 engaging over a pin 75 fixed to the bolt 70. Near its lower end lever 72 carries on one face thereof a pin 76 riding in a groove in the locking collar 33. This collar 33 is carried by a pull rod 31 having a handle or pull member 32 projecting forwardly of the front face of the casing 30 and in easy reach of the driver and is adapted to be engaged, when the rod is pulled forwardly, into locking position, by a bolt 34 of a lock accessible from the forward face of the casing to a key by which it may be unlocked. The rear end of the rod 31 may, if desired, be connected by a cable 28 with a pedal lock such as is described in the application above mentioned of which this is a division and by which the rod is normally urged inward to unlocking position.

While the lighting circuits may be locked in any position desired, whether entirely off or the curb light only lighted, the lights being dimmed or on full, it is always desirable to lock the car with the ignition off. For this reason one notch 66 only has been provided for the disk 48. To further insure that the ignition be off when locking is effected, provision is made by which should this switch not be in off position, it will be thrown to such position on the locking of the car. For this purpose the rear face of the disk 48 is provided with an outstanding cam portion 80, shown best in Figure 4, so positioned that if the disk 48 is turned to close the ignition switch the locking bolt 70 will impinge thereon and urge the disk 48 in a direction to open the ignition switch. This action is shown in Figure 8 in which a slight modification of the locking bolt is shown, it being formed integral with the upper end of the actuating lever, the lever being indicated at 72' and the bolt being indicated at 70'.

From this description it will be seen that this invention provides a locking mechanism by which it is insured that the ignition circuit is open when the car is locked, but wherein the lighting circuit may be locked in any position of adjustment desired so that it may not be tampered with.

Having thus described an embodiment of

this invention it should be evident to those skilled in the art that many changes and modifications might be made therein without departing from its spirit or scope as defined by the appended claims.

65

I claim:

1. In an automobile, an ignition switch, a lighting switch, each of said switches including a pivoted disk, said ignition switch disk having a peripheral notch therein, and said lighting switch having a plurality of such notches therein, a bolt projectable through the notch in said ignition switch disk and any one of said notches in said lighting switch disk to lock said ignition switch and said lighting switch in any of a plurality of positions, and a cam member carried by said ignition switch disk and engageable by said plunger when said switch is in "on" position to move it to "off" position as the bolt is projected.

70

2. In combination, a lighting switch comprising a pivoted disk, an ignition switch comprising a pivoted disk lying in the plane of said lighting switch disk and adjacent thereto, said disks having peripheral notches, and a locking element movable transverse to the plane of said disks and engageable within said notches to lock said disks from turning.

85

3. In combination, a lighting switch comprising a pivoted disk, an ignition switch comprising a pivoted disk lying in the plane of said lighting switch disk, said lighting switch disk having a plurality of peripheral notches, and said ignition disk having a single notch, and a plunger projectable between said disks transversely of the plane thereof and engaging in said single notch of said ignition switch disk and in any of said notches of said lighting switch disk for preventing said disks from turning.

90

4. In combination, a lighting switch comprising a pivoted disk, an ignition switch comprising a pivoted disk lying in the plane of said lighting switch disk, said lighting switch disk having a plurality of peripheral notches, and said ignition disk having a single peripheral notch, a plunger projectable between said disks transversely of the plane thereof and engaging in said single notch of said ignition switch disk and in any of said notches of said lighting switch disk for preventing said disks from turning, and means for locking said plunger in projected position.

100

In testimony whereof I have affixed my signature:

EDGAR J. MARTEL
